UNITED STATES PATENT OFFICE.

WILLIAM J. O. BRYON, JR., OF NEW YORK, N. Y.

EXERCISING-MACHINE.

SPECIFICATION forming part of Letters Patent No. 499,205, dated June 13, 1893.

Application filed January 29, 1890. Serial No. 338,480. (No model.)

To all whom it may concern:

Be it known that I, WILLIAM J. O. BRYON, Jr., a citizen of the United States, and a resident of the city, county, and State of New York, have invented new and useful Improvements in Exercising Apparatus, of which the following, taken in connection with the accompanying drawings, is a specification.

My invention relates more particularly to that class of exercising apparatus adapted to be permanently, or otherwise, attached to the wall or other suitable object in a room where, by the use of pulleys, weights, connecting ropes, &c., suitably arranged, various forms of physical exercise, bringing into action the different muscles of the body, may be obtained;—and my invention consists more particularly in the construction of two pulleys, and in the manner of arrangement, and combination of the same with the several other parts comprising the apparatus, as will hereinafter be set forth, whereby a single apparatus may be adapted for various kinds of exercise, for which, apparatus adapted for the same purposes and of a similar character heretofore used, have required the use of three or more pulleys, and double the amount of weight or other resisting power, or two or more apparatus of special construction have been used to accomplish the same results obtained by the use of my improved apparatus; and my invention also consists in the arrangement and mode of connection of the several parts forming the apparatus, in a small and compact form, as to especially adapt it for shipping purposes, &c., without necessitating taking it apart for such purpose, thereby rendering it especially applicable for home use, as well as gymnasium, &c., in that when the same is unpacked, it is only necessary to fasten the same permanently to some stationary object, and have it ready for use, thereby obviating the inconvenience and difficulty usually attending the placing of such apparatus in position by persons unskilled in the art, when such apparatus is shipped in detached parts; and my invention also consists in other arrangement of parts, and details of construction as will hereinafter be set forth, and pointed out in the claims.

The object of my invention is to provide an apparatus of few parts, and of cheap and

simple construction, combining the necessary requisites of strength, durability, &c., that may be adapted for different kinds of exercise, usually requiring the use of an apparatus of a greater number and more complicated parts, and produced at a correspondingly greater cost, or two or more apparatus of special construction; hence my invention.

Referring to the drawings:—Figure 1 represents a side elevation of my improved apparatus in position for use. Fig. 2 represents a front view of the same, showing two separate apparatus. Figs. 3, 4, 5, 6, 7, and 8, represent different views of detail parts all to be referred to hereinafter. Fig. 9 represents a side elevation of my improved apparatus, and Fig. 10 represents a section of the same, as adapted for “foot-exercise,” and Fig. 11 an end view of the supplemental apparatus or part 1.

Referring to Figs. 1 and 2, I have shown a side and a front view respectively, of a part of my improved apparatus, as adapted for certain kinds of exercise, Fig. 2 showing two of said parts, arranged side by side, merely to show how two of the same may be arranged to be operated by the one person; and it consists of a supporting plate A (shown in detail in Fig. 3), adapted to be secured to the wall of a room or other suitable stationary object, and is provided with two lugs or projections a', a', thereon, through and between which a pin c² extends, and is secured at its upper end by a nut c³, and at its lower end is provided with an eye c⁴, in which one end of the rope A' is adapted to be adjustably connected as and for the purpose as will hereinafter be set forth. A pulley consisting of the wheel or sheave c, and supporting frame C is swiveled by means of the latter, on the pin c², as more clearly shown in Fig. 3, the object of such swiveled connection being to allow said pulley to adjust itself, to any angle at which the rope A', passing over the same, may be drawn either by the operator directly, or through the medium of other means, as will hereinafter be described. Said rope A', in the instance shown, passes over said swiveled pulley, and down under the sheave of a loose pulley B, (shown in detail in Fig. 4,) which is detachably attached to a weight carrier D, and from thence upward

and is detachably connected at its end, by means of a hook secured thereto, with the eye c^4 , in said pin c^2 . The said loose pulley B consists of the sheave b , and guard b' which extends around the same with an opening b^2 , therein for the ready admission of the rope or cord and the hook b^3 located on said guard as the means for detachable connection of said pulley to a desired object, which arrangement and construction of said loose pulley and end of the rope A' for detachable connection with engaging parts form one of the essential features of my invention. The said weight carrier D (shown in detail in Figs 5 and 8) consists of a plate provided with a circular shank or stem E which is fastened at its upper end and provided with an eye e^2 therein, as a means by which either the loose pulley B or the end of the rope A' , according to the exercise for which the apparatus may be adapted, may be detachably attached, and said carrier is provided at each end with a groove d therein, for the admission of the vertically arranged guide-rods G, and as a means by which said carrier may be guided when elevated or lowered, by means of the rope A; and said grooves d are provided with an inner groove d' to form a pocket for the reception of a suitable packing, in the present instance, consisting of a piece of felt d^5 , adapted to be wrapped around the rods G, and the same is held in position in said pocket d' by a plate forming a cap D', adapted to be secured to the ends of said carrier, and which is provided with a groove d^3 corresponding to the groove in the carrier D, and with a recess d^4 for the reception of the ends of the packing d^5 (as clearly shown in Fig. 8), by which method I form noiseless bearings, and when the packing becomes worn, the same may be easily replaced. The character of weights I use in connection with said carrier, is shown in detail in Fig. 7, and consists in the instance shown of a plate E provided with a central opening e^3 and an outer connecting slot e^4 to enable the weight to be slipped on the stem of the carrier at its upper flattened end until the central opening is reached which is of a size corresponding to the stem E', to allow said weight to drop and rest upon the top of the carrier. Said weights are provided with a flange e^5 around the opening e^3 on their upper surfaces and with a corresponding groove e^6 in the lower side, in a manner to allow the flange on one weight to enter the corresponding groove in the upper weight and this acts in connection with the stem of the weight carrier to hold the weights in position, as will be readily understood. The said guide rods G. G., at their upper ends are screwed in the arms a^2 a^2 , of the frame A, and at their lower ends are provided with a foot g , which may be a nut or a flange cast thereon, and which are adapted to rest in openings or recesses, in a sole plate F, as more clearly shown in Fig. 5, which plate is adapted to be secured

to the floor immediately beneath the upper plate or frame A, and the said feet g are held in position in said openings or recesses in the sole F by a retaining plate F' which is provided with openings therein, of a size corresponding to the diameter of the guide-rods, and when the apparatus is put together, said retaining plate F' is slipped over the tops of the said guide rods G, the ends of the latter entering the opening in said plate F' which plate is then secured, by screws, bolts or otherwise to the said sole plate F', and thus lock the lower ends of said guide rods in a fixed position, the advantage of which method of connection of parts, in the reduced time and ease of putting together, the same, and the extra strength and durability gained, will be readily understood by those skilled in the art.

To illustrate the manner in which that part of my apparatus above described may be adapted for different kinds of physical exercise by means of my improved mode of construction of the several parts forming the same, I have shown in dotted lines in Fig. 1, the apparatus arranged for "shoulder exercise," so-called, accomplished by detaching the loose pulley B from the weight carrier D, and attaching it to a hook or eye adapted to be secured in the ceiling or some stationary object located above the pulley C, and running the rope A' through the same as shown and detaching the opposite end from the eye c^4 , in the pin c^2 , and attaching it to the eye in the stem of the weight carrier, in a manner as shown in Fig. 9 (Sheet 2), by which arrangement I employ the two original pulleys only, where others heretofore used for the same character of exercise employ an extra pulley, and also by means of said arrangement the weight acts as a "dead weight" so-called, upon the upper loose pulley B, the swiveled pulley C merely acting as an anti-friction wheel, as will be readily understood by those skilled in the art. Another advantage is also gained in that by such arrangement, it requires an increased power to operate, or raise and lower, the weight, by reason of the use of one pulley only, instead of diminishing the power to be exerted to operate the weight, as would be the case if an extra or third pulley were employed as heretofore, the advantage of which is obvious.

Referring to Fig. 9, I have shown in connection with the apparatus hereinbefore described, a supplemental apparatus or device, adapted to be used in connection with the former for certain kinds of exercise, and which forms a part thereof, and it consists of a frame I provided with two sides supported by connecting rungs i^3 as more clearly shown in Fig. 11. Said sides are provided on their upper edges with grooves forming tracks in which the wheels j , attached to a sliding seat J, are adapted to operate, and on their inner faces are provided with grooves in which rods i , adapted for the support of foot rests i' are

dove-tailed, in order to slide and operate freely thereon when desired, and for the purpose to be hereinafter set forth.

The apparatus as represented in Fig. 9 is adapted for what is termed "rowing exercise" as distinctive from other forms of exercise. In this instance, the loose pulley B is attached to an eye f^2 secured, in the instance shown, in the base plate F, although it is obvious that the same may be secured in the floor, and one end of the rope is attached to the weight carrier as shown, and extends therefrom up over the swiveled pulley C', which latter may in some instances be stationary, and down under the loose pulley, and is provided at its free end with a suitable handle a^3 , for the grasp of the operator, and the foot-rests are in this case held stationary by means of a pin adapted to extend through openings i^3 in the sides of the frame, into openings located in the foot-rest-supporting rods i (see Fig. 10) or it is obvious that said rods i might be secured in a stationary position by hook and eye, or other suitable mode of connection, and the seat is left free to slide freely on said frame. By this method of arrangement of parts, exercise similar to that of rowing may be obtained.

Referring to Fig. 10 I have shown the apparatus as adapted for "foot-exercise." In the instance shown the position of the frame I is reversed, and the free end of the rope is attached to the rear end of one of the sliding rods i , which are connected at their front ends by the foot-rest i' to enable the same to slide in unison, and said rods are released from their locked positions, and the sliding seat secured in a fixed position by a pin j^2 , or other suitable method, in a manner to allow the operator to rest on a fixed seat, and operate the sliding rods i and the apparatus connected thereto, by the feet and legs, or in case an alternate action of the sliding rods may be desired each may be provided with a separate foot rest, and the rope of two separate apparatus be connected to the end of each sliding rod. Again,—by providing a wheel or roller at the rear end of the sides of the frame I, as shown at i^3 in Fig. 9, the end of the rope A' may be passed

around the same and connected to the end 50 of the sliding rod i , without turning said frame, as shown in Fig. 10, in case the same is secured to the floor as will appear obvious.

I do not wish to be understood as claiming herein anything shown in my Patent No. 55 254,103, granted February 28, 1882, my present invention consisting in certain improvements upon my previous invention set forth in said patent.

Having thus set forth my invention, what 60 I claim as new, and desire to secure by Letters Patent of the United States, is—

1. In an exercising apparatus, in combination with guide-rods, a weight-carrier, consisting of a plate or block provided with openings for the admission of said guide-rods, and a connecting groove or slit, packing, formed of felt or other suitable material adapted to be inserted in the guide-rod openings in said plate or block with its ends projecting in the 70 said connecting groove or slit, and be held in position therein by a screw or its equivalent, substantially as and for the purpose set forth.

2. In an exercising apparatus, the combination of the supporting frame, guide-rods supported at their upper ends by said supporting frame, and at their lower ends provided with an enlarged foot, a sole-plate provided with openings for the reception of said feet, and a retaining plate adapted to be secured on said 80 sole plate to lock said feet of the guide-rods in position, substantially as described and for the purpose set forth.

3. In an exercising apparatus the combination with the guide rods, and a weight carrier thereon, having an eye e^2 , of a bracket carrying a permanent pulley c , the stationary eye c^4 at the top of the apparatus, the stationary eye f^2 at the base of the apparatus, the detachable pulley B having a hook by 90 which it may be connected with either of the eyes e^2 and f^2 , and the rope A', having a handle and a hook for attachment to the eye e^2 or to the eye c^4 , substantially as set forth.
